CLAIM

The ornamental design for an education toy kit, as shown and described.

DESCRIPTION

FIG. 1 is a plan view of the entire kit, including a backboard, seven rotating parts, and a tile;

FIG. 2 is a perspective view of the backboard of FIG. 1;

FIG. 3 is a plan view of the backboard of FIG. 2;

FIG. 4 is a rear view of the backboard of FIG. 2;

FIG. 5 is a perspective view of the first rotating part of FIG. 1;

FIG. 6 is a plan view of the first rotating part of FIG. 5;

FIG. 7 is a perspective view of the second rotating part of FIG. 1;

FIG. 8 is a plan view of the second rotating part FIG. 7;

FIG. 9 is a perspective view of the third rotating part of FIG. 1;

FIG. 10 is a plan view of the third rotating part of FIG. 9;

FIG. 11 is a perspective view of the fourth rotating part of FIG. 1;

FIG. 12 is a plan view of the fourth rotating part of FIG. 11;

FIG. 13 is a perspective view of the fifth rotating part of FIG. 1;

FIG. 14 is a plan view of the fifth rotating part of FIG. 13;

FIG. 15 is a perspective view of the sixth rotating part FIG. 1;

FIG. 16 is a plan view of the sixth rotating part of FIG. 15;

FIG. 17 is a perspective view of the seventh rotating part of FIG. 1;

FIG. 18 is a plan view of the seventh rotating part of FIG. 17;

FIG. 19 is a perspective view of the tile of FIG. 1; and,

FIG. 20 is a plan view of the tile of FIG. 19.
